UNITED STATES PATENT OFFICE

147,537

DESIGN FOR A HAIRBRUSH FRAME

Alan Daniels, New York, N. Y., assignor to Baby World Company, Inc., New York, N. Y., a corporation of New York

Application September 7, 1946, Serial No. 133,137

Term of patent 7 years

(Cl. D86—10)

To all whom it may concern:

Be it known that I, Alan Daniels, a citizen of the United States, residing at New York city, in the county of New York and State of New York, have invented a new, original, and ornamental Design for a Hair Brush Frame, of which the following is a specification, reference being had to the accompanying drawing, forming part thereof.

In the drawing:

Fig. 1 is a top plan view of a hair brush frame, showing my new design;

Fig. 2 is a side elevational view thereof.

I claim:

The ornamental design for a hair brush frame, substantially as shown.

ALAN DANIELS.
